HAND FIRE EXTINGUISHER

Stewart Boal, Chicago, Ill., assignor to Randolph Laboratories, Inc., Chicago, Ill., a corporation of Illinois

Application May 14, 1942, Serial No. 442,904

1 Claim. (Cl. 169—31)

This invention relates to a portable fire extinguisher using carbon dioxide as the extinguishing agent, and which is so designed and constructed that the extinguisher may be carried, directed, and operated by one hand, leaving the other hand entirely free.

One of the objects of my invention is to produce a fixed self-directing outlet as an integral part of the device and located in alignment with the thumb-actuated trigger and handle so that the extinguishing fluid may be accurately directed and controlled by the use of but one hand.

Another object is to provide for better control of the direction and quantity of the extinguishing fluid by mounting the trigger directly over the handle so that it may be readily actuated by downward pressure of the thumb which would be in its natural position when the hand grasps the handle.

Another object is to provide a horn for controlling the proper admixture of the discharged carbon dioxide with a minimum entrapment of air, and means for mounting the horn in a fixed position upon the extinguisher and opposite the handle or grip and the trigger.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawing, and while there is shown therein a preferred embodiment, it is to be understood that the same is susceptible of modification and change, and comprehends other details, arrangements of parts, features and constructions without departing from the spirit of the invention.

In the drawing:

Figure 1 is a side view of the fire extinguisher. Figure 2 is an enlarged fragmentary view in vertical cross-section of the upper portion of the fire extinguisher showing the operating mechanism and mounting of the horn in fixed position upon the extinguisher.

I have embodied the foregoing objects in a construction which affords an easily portable mechanism, a convenient carrying handle in permanent position readily noticeable to make the method of carrying obvious, a nozzle in permanent position and readily noticeable to make the aiming obvious, a convenient thumb-actuated trigger or lever immediately over the handle for

the purpose of accurately controlling the liberating mechanism, a horn, one end of which surrounds the nozzle and which is anchored in operating position by the nozzle itself.

5 Referring more particularly to the novel illustrative embodiment disclosed in the drawing, the numeral 1 represents the usual tubular or cylinder container having a threaded opening 2 at the top of the cylinder. A valve assembly 3 made of brass or other suitable material is provided with a threaded portion 4 which screws into the threaded opening 2.

The valve assembly or housing 3 contains a valve mechanism comprising a plunger 5 having a detachable valve 5a carrying a packing ring 6 or washer, which is adapted to be raised and form sealing engagement with the valve seat 7. The valve is designed to be held in closed position by an expansible spring 8 and the pressure of the

10 carbon dioxide until the plunger 5 is manually depressed by a downward motion on the trigger 9. Trigger 9 is attached to a lever 10 which is pivoted at 11. Intermediate the pivot 11 and the trigger 9 is an aperture 12 for receiving a locking pin 13, which when in place, prevents the lever from being sufficiently depressed to actuate the plunger 5 and unseat the valve. It will thus be seen that when the pin 13 is removed and the trigger 9 is pushed downwardly,

15 a downward pressure is exerted upon the plunger 5 which opens the valve and permits a passage of the fluid upwards around the valve and out through the nozzle aperture 14 which connects through adjoining openings with interior of the 20 valve assembly. The handle 15 is screwed into the housing 3 at an opening 16 in the housing, which opening is placed at a suitable distance directly below the trigger 9 to facilitate operation. A fixed stationary horn 17 is positioned

25 on the housing directly opposite to or in alignment with the handle 15, and is so designed as to be held in place by screwing the cap or nozzle 18 over the nozzle connector 19 against an in-turned flange 20 on the base of the horn and thereby anchoring the horn in fixed position. It will thus be seen that when the cap or nozzle 18 is screwed tightly against the inwardly projecting annular flange of the horn 17 that the horn is held in a fixed position and is in a straight line

30 with the handle 15 and the trigger 9.

Having thus described the invention, I claim:
A one hand operation portable fire extinguisher comprising a cylinder adapted to contain carbon dioxide under pressure, a valve for releasing the contents of the cylinder, a nozzle and a rigid

and stationary horn in fixed position for directing and controlling the discharge of said contents, a handle for carrying the fire extinguisher, said handle being located diametrically opposite said horn and nozzle, a thumb-actuated trigger located immediately above said handle, means whereby the valve is held open for dis-

charge of the contents when the trigger is depressed and means comprising a locking pin extending through said trigger for preventing accidental displacement of said trigger when said valve is closed.

5 STEWART BOAL.
